UNITED STATES PATENT OFFICE.

LOUIS EMILE CELESTIN LELU, OF PARIS, FRANCE.

BIDET.

SPECIFICATION forming part of Letters Patent No. 628,162, dated July 4, 1899.

Application filed August 23, 1898. Serial No. 689,309. (No model.)

To all whom it may concern:

Be it known that I, LOUIS EMILE CELESTIN LELU, a citizen of France, residing at Paris, France, have invented certain new and useful 5 Improvements in Bidets, of which the following is a specification.

My invention is designed to furnish an improved form of bidets; and it includes a receptacle fitted to a frame in the shape of a 10 seat and adapted to be covered when not in use and a back adapted to serve as a reservoir for the water to be used.

The invention includes, further, certain improved details of construction, as will be more 15 fully hereinafter set forth and particularly claimed.

In the drawings, Figure 1 is a sectional view through the device and through the operating parts. Fig. 2 is a plan with the cover removed 20 and with the back omitted. Fig. 3 is a sectional view of a modification.

In Fig. 1 the support is provided with legs and a frame, and within this frame is located a receptacle A, adapted to hold the water for 25 bathing purposes, and this receptacle is fitted to a frame B, supported upon springs C, which thus allow a certain amount of yielding to the receptacle, for a purpose hereinafter to be described. A cover X conceals the receptacle A 30 when it is not in use and enables the device to be used as a seat. This cover is removable and may be displaced whenever desired. A back is provided to add to the comfort of the user when occupied as a seat, and I utilize 35 this back by placing within it a reservoir U, adapted to contain the water for use in the bath. The tank K is provided to receive the waste from the receptacle A, and this is located beneath the seat and is in connection 40 with the receptacle A by an overflow O and a flexible tube N'. The receptacle A has a depression Q covered by a plate V, having inclined perforations R, and the water passes into this depression through the pipe M from 45 the reservoir U, the tube F, and the flexible tube N through the valve-opening. A valve S covers this opening and is held to its seat by a rod D, pivoted at E at its lower end and at its upper end to the valve-stem. When 50 the frame B and the chamber A are not in use,

the tension of the springs C keeps the valve-seat pressed tightly against the valve and prevents the flow of water; but when the bath is being used the weight of the person depresses the receptacle A against the springs C, thus 55 opening the valve and allowing the water to flow into the receptacle, while the inclination of the series of perforations R will direct the flow to the front. The water will continue to rise in the chamber A until it reaches the 60 overflow O, by which it will pass to the tank K. After the bath has been used it is necessary to provide for the discharge of the water below the level of the outlet O, and this is done through a valved outlet discharging into 65 the tank K from the depression Q. When the receptacle is depressed, the outlet is closed by the valve S'; but when it rises the valve-seat moves away from the valve, leaving an opening, and the water flows out into the tank 70 K through the tube L, around the valve-stem G, which is guided in the tube H, and through the tube I into the tank.

In Fig. 3 I have shown a modification in which the water passes through the valve-opening S² and passage A² and from thence through the passage C² into the receptacle, and a valve F², carried upon a stem G² and having a float E² at its upper end, is adapted to partially close the opening between the channels A² and C² when the water in the receptacle has lifted the float, and this serves to check the influence of the water and make it more gradual, the valve F² being slotted or provided with channels, so as to allow the flow. By 80 this construction the water flows in very rapidly at first, and then its flow is retarded. The float E² is contained in a chamber and this has communication with the receptacle through the passage D². 90

What I claim is—

1. A bidet comprising a suitable frame, a receptacle under spring tension, a water-supply, a valve controlling the same operated by the movement of the receptacle and a drain-outlet with a valve controlling the same also operated by the movement of the receptacle, substantially as described. 95

2. A bidet comprising a frame, a receptacle carried thereby and movable vertically, 100

a main supply-valve, a passage between the same and the receptacle, a valve in said passage having channels to allow a limited quantity of water to pass when the valve is closed
5 on its seat and a float connected with said valve for operating the same, substantially as described.

In witness whereof I have hereunto set my hand in presence of two witnesses.

LOUIS EMILE CELESTIN LELU.
